(57) **CLAIM**

The ornamental design for a toy animal, as shown and described.

DESCRIPTION

FIG. 1 is a perspective view from above, to the front and to the left side of a first embodiment of the new design for a toy animal;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof;

FIG. 8 is perspective view from above, to the front and to the left side of a second embodiment of the new design for a toy animal;

FIG. 9 is a front view thereof;

FIG. 10 is a rear view thereof;

FIG. 11 is a right side view thereof;

FIG. 12 is a left side view thereof;

FIG. 13 is a top plan view thereof; and,

FIG. 14 is a bottom plan view thereof.

In the drawings, the broken lines are for the purpose of illustrating portions of the article that form no part of the claimed design. The dash-dot broken lines represent the bounds of the claim which form no part of the claimed design.
